UNITED STATES PATENT OFFICE.

WILLIAM H. ZEIGLER, OF LONG ISLAND CITY, NEW YORK.

SPARK-PLUG.

1,344,530.

Specification of Letters Patent. Patented June 22, 1920.

Application filed September 22, 1919. Serial No. 325,500.

To all whom it may concern:

Be it known that I, WILLIAM H. ZEIGLER, a citizen of the United States, residing at Long Island City, in the county of Queens and State of New York, have invented new and useful Improvements in Spark-Plugs, of which the following is a specification.

This invention relates to spark plugs for use in connection with explosive engines, and 10 more particularly to carbon removers therefor.

Some of the objects of the invention are: to provide carbon removing means at the lower end of one of the electrodes of a spark 15 plug, said means embodying a plurality of spark points and being adapted to reciprocate under the action of the explosion within the spark chamber to which a plug is applied and the ordinary vibrations of the engine in operation, to minimize the accumulation 20 of carbon; to provide a reciprocating element at the lower end of one electrode having a plurality of spark points and gaps reducing the possibility of spark interruption from carbon accumulations to a minimum and rendering the plug practically infallible for the intermittent continuity of 25 sparks; to provide a plug in which is employed a bushing for associating the core 30 with the shell of the plug, which is in reality the ground electrode and so arranged and of such construction as to establish the proper spark gaps regardless of the position of the cleaning element and its spark points. With 35 these and other objects in view the invention resides in the particular construction and correlation of parts which will be fully described in the following specification and which are illustrated in the accompanying drawings forming a part of this specification.

In the drawings:—

Figure 1 is a central vertical sectional view of a spark plug embodying my invention.

Fig. 2 is a bottom plan view; the cleaning element is associated with the electrode upon which it is adapted to reciprocate.

Referring now to the drawing, it will be seen, that the spark plug is to comprise an outer shell or casing 10 which accommodates a porcelain core 11 carrying the usual central electrode 12. The electrode 12 is of sufficient length to receive at the upper end

thereof a terminal nut 13 having the usual 55 terminal clip slot and a lock nut with which and a second nut on the electrode arranged within the hollow apron 14 of the core 11, serve to hold the electrode in place. A copper and asbestos gasket is arranged between 60 the nut and one wall of the cavity formed on the apron 14. The core is provided with an enlarged portion 15 disposed intermediate the length of the core to provide shoulders 15^a and 15^b. Copper and asbestos gaskets 65 encircle the core 11 and in the assemblage of the core 11 with the shell 10 the gasket 16 will be interposed between the shoulder 15^a, formed on the enlarged portion 15 and shoulder 10^a provided by the varied 70 bores in the shell. The bore 17 in the shell 10 is screw threaded to accommodate a threaded bushing 18. Interposed between the upper end of the bushing 18 and the shoulders 15^b is a copper and asbestos gasket 75 19. The gaskets 16 and 19 serve to provide tight joints to thwart the tendency of the hot gases to find their way between the parts thereby eliminating cracking of the porcelain core and enabling it to stand a high degree of heat. The bushing 18 is of such 80 length that a portion thereof protrudes from the shell, said portion being provided with a plurality of flat faces to accommodate a wrench or the like to facilitate its removal or 85 its being fitted to the shell 10. The lower end of the electrode 12 extends below the lower end of the core 11 and has arranged thereon for reciprocating action and turning action as well, a cleaning element 20, 90 comprising a porcelain member 21 having a bore 22 slightly larger in diameter than the diameter of the electrode 12 so that the member 21 may freely reciprocate or rotate as the case may be. An annular metallic member 95 23 is arranged upon the enlarged portion 21^a of the member 21 and is provided with a plurality of spark points 24, adapted to lie in juxtaposition to a ferrule or nut 25 at the extreme end of the electrode 12 which limits 100 the downward movement of the cleaning element 20. The enlarged portion 21^a is adapted to engage the apron 14 to limit the upward movement of the cleaning element 20. The range of movements of the cleaning element 20 is sufficient to give it an impetus 105 which will remove any carbon that may accumulative on the end of the electrode 12

and will loosen and shake off any carbon that may accumulate about the spark points 24.

From the construction and arrangement 5 of parts constituting the plug it will be manifest that the accumulation of carbon or soot will be reduced to minimum and that the possibility of spark interruption is practically entirely eliminated.

10 What is claimed as new is:—

1. In a spark plug, a plurality of electrodes, a cleaning element arranged for reciprocatory movement on one of said electrodes, spark points carried by said cleaning 15 element intervening the electrodes to provide a plurality of spark gaps between said electrodes.

2. In a spark plug, a plurality of electrodes, a movable non conducting cleaning 20 element arranged on one of said electrodes and responsive to the varying pressures within the engine and vibrations thereof, spark points carried by said cleaning element intervening the electrodes to provide a 25 plurality of spark gaps between said electrodes.

3. In a spark plug, a central electrode and a ground electrode, a movable porcelain cleaning element having a limited movement arranged on the central electrode, an 30 annular metallic member having a plurality of spark points carried by the cleaning element, the spark points intervening the electrodes to provide a spark gap between the

central electrode and the spark points, and a 35 spark gap between the spark points and the ground electrode.

4. In a spark plug, a plurality of electrodes, a plurality of spark points intervening 40 said electrodes permitting spark occurrence through the spark points singly or collectively and means arranged for reciprocating on one of said electrodes for removing carbon accumulation.

5. A spark plug comprising a shell em- 45 bodying a non-conducting core and a bushing, said bushing constituting an annular ground electrode, a central electrode carried by said core, a carbon cleaning element arranged for reciprocation on the central elec- 50 trode, radially disposed spark points carried by said cleaning element and intervening both of said electrodes.

6. A spark plug comprising a shell em- 55 bodying a non-conducting core and a bush- 60 ing, said bushing constituting an annular ground electrode, a central electrode carried by said core, a carbon cleaning element arranged for reciprocation on the central elec- 65 trode, radially disposed spark points car- 65 ried by said cleaning element and intervening both of said electrodes and a conduct- ing ferrule on the central electrode to limit the downward movement of the cleaning element.

In testimony whereof I hereby affix my signature.

WILLIAM H. ZEIGLER.
